(57) **CLAIM**

The ornamental design for a hood for road construction machine, as shown and described

DESCRIPTION

FIG. 1 is a left side view of the design for a hood for road construction machine of the present invention.

FIG. 2 is a front side view of the design for a hood for road construction machine of FIG. 1.

FIG. 3 is a right side view of the design for a hood for road construction machine of FIG. 1.

FIG. 4 is a rear side view of the design for a hood for road construction machine of FIG. 1.

FIG. 5 is a top side view of the design for a hood for road construction machine of FIG. 1.

FIG. 6 is a bottom side view of the design for a hood for road construction machine of FIG. 1.

FIG. 7 is a perspective view of the front side, left side and top side of the design for a hood for road construction machine of FIG. 1.

FIG. 8 is a further perspective view of the front side, right side and top side of the design for a hood for road construction machine of FIG. 1.

FIG. 9 is a left side view of a second embodiment of the design for a hood for road construction machine of the present invention.

FIG. 10 is a front side view of a second embodiment of the design for a hood for road construction machine of FIG. 9.

FIG. 11 is a right side view of a second embodiment of the design for a hood for road construction machine of FIG. 9.

FIG. 12 is a rear side view of a second embodiment of the design for a hood for road construction machine of FIG. 9.

FIG. 13 is a top side view of a second embodiment of the design for a hood for road construction machine of FIG. 9.

FIG. 14 is a bottom side view of a second embodiment of the design for a hood for road construction machine of FIG. 9.

FIG. 15 is a perspective view of the front side, left side and top side of a second embodiment of the design for a hood for road construction machine of FIG. 9; and,

FIG. 16 is a further perspective view of the front side, right side and top side of a second embodiment of the design for a hood for road construction machine of FIG. 9.
